(57) CLAIM

The ornamental design for a golf club head, as shown and described.

DESCRIPTION

FIG. 1 is a top, heel side perspective view of a golf club head embodying our new design;

FIG. 2 is a top side view thereof;

FIG. 3 is a bottom side view thereof;

FIG. 4 is a front side view thereof;

FIG. 5 is a back side view thereof;

FIG. 6 is a heel side view thereof; and,

FIG. 7 is a toe side view thereof.

All features illustrated in phantom line are expressly disclaimed and form no part of the claimed design.
